UNITED STATES PATENT OFFICE

KARL F. SNOW, OF BRECKSVILLE, OHIO, ASSIGNOR TO THE C. O. BARTLETT & SNOW COMPANY, OF CLEVELAND, OHIO, A CORPORATION OF OHIO

UPSETTING DEVICE FOR BARRELS AND LIKE ARTICLES

Application filed June 25, 1930. Serial No. 463,739.

My invention, relating as indicated, to barrel upsetting devices, has specific reference to an apparatus adapted to receive barrels in a horizontal position and automatically upset the same onto a conveyor, or like means, whereby such barrels may be conveyed to a suitable distant point. Considerable difficulty has been experienced in the construction of barrel upsetting devices capable of being employed for the purpose of upsetting barrels after the same have been painted or coated due to the fact that such upsetting device in order to efficiently accomplish its purpose must be designed so that no contact will be had thereby with the freshly coated body of the barrel. A further requirement of a barrel upsetting device is that it shall be capable of efficiently accomplishing its purpose and yet be entirely automatic in its operation so that supervision thereof by workmen is unnecessary during the upsetting of successive barrels.

It is among the objects of my invention to provide a barrel upsetting device which shall have all of the above named desirable characteristics. Other objects of my invention will appear as the description proceeds. To the accomplishment of the foregoing and related ends, said invention, then, consists of the means hereinafter fully described and particularly pointed out in the claims.

The annexed drawings and the following description set forth in detail certain mechanism embodying the invention, such drawings closed means constituting, however, but one of various mechanical forms in which the principle of the invention may be used.

In said annexed drawings:

Fig. 1 is a perspective view of the upsetting device comprising my invention, showing the upsetting arms thereof in substantially vertical position; Fig. 2 is a perspective view of the upsetting device illustrated in Fig. 1, showing the barrel upsetting arms in horizontal position; and Fig. 3 is a side elevational view of the apparatus illustrated in Figs. 1 and 2.

Referring more specifically to the drawings, and more especially to Figs. 1 and 2, the barrel upsetting device comprising my

invention consists of a frame, generally indicated by the ordinal 1, which carries bearing blocks 2 on one end thereof in which bearings is rotatably mounted a shaft 3 which has terminally secured thereto a crank arm 4. Secured to the shaft 3 at spaced points intermediately of the bearings 2 are arms 5 which have secured thereto bracket members 6 and 7. The bracket member 7 has secured thereto laterally extending plate members 8 for the purpose hereinafter more fully described.

Secured to the frame 1 at 9 is a shaft 10 which extends transversely thereof and which has oscillatably mounted thereon a lever 11, one terminal 12 of which has secured thereto a retractile spring 13 which is secured at its other end to a hook or like anchorage 14 adjustably secured to a bracket 15 which is secured to a portion of the frame 1. The other terminal 16 of the lever 11 is tapered similarly to the taper of the bracket member 7 so that the upper edges of the members 7 and 16 preferably lie in the same plane.

Mounted on a plate 17, which is secured and extends transversely of the frame 1, is a switch box 18 which has a wheel 19 secured to the actuating lever 20 thereof. This wheel is normally in contact with the lever 11. Mounted on that end of the frame 1 opposite the shaft 3 is another switch box 21 which also has a wheel 22 secured to the actuating lever 23 thereof, which wheel is adapted to be engaged by the terminal 24 of one of the arms 5.

Mounted on the frame 1, preferably at the end thereof opposite the shaft 3, is a motor 25 which is in driving communication with a speed reducer 26. To the shaft of the speed reducer 26 is secured a crank arm 27 which has rotatably secured thereto a pitman 28. The pitman 28 is oscillatably secured at its other terminal to the crank arm 4. The motor 25 may be provided with the common type of electro-magnetic brake 29 which is actuated in the usual manner by a relay 30 when the current to such motor is interrupted.

The frame 1 may have mounted thereon on one side a longitudinally extending stop member 31 which will prevent the barrels from rolling off from the arms 5.

The operation of the apparatus comprising my invention may briefly be described as follows. With the upsetting arms in the horizontal position as indicated in Fig. 2, a barrel is rolled onto the brackets 6 and 7 which brackets are oppositely tapered and spaced so that the freshly painted or coated barrel is supported only on the chime rings thereof, thereby preventing the possibility of any marring of the freshly coated surface. The stop 31 will prevent any barrels from rolling off the upsetting apparatus, and therefore obviates the necessity of any personal attention to the upsetting device by an operator.

When the barrels have rolled onto the brackets 6 and 7, the chime ring of such barrel will depress the portion 16 of the lever 11 which, in turn, will depress the wheel 19 and actuating lever 20 of the switch 18 which establishes the electrical communication to the motor 25. The motor 25 through the speed reducer 26 will rotate the crank arm 27, causing a corresponding rotation of the crank arm 4, thereby upsetting the barrel as most clearly shown in Fig. 3. The provision of the plate members 8 associated with the bracket member 7 prevents the barrel from sliding off from the upsetting arms 5 until such barrel has been elevated to a position so that such barrel may fall onto a roll table 32 which will convey the barrels away from the upsetting machine. The continued rotation of the crank arm 27 will effect a return of the arms 5 from the vertical position just described to a horizontal position, upon the attainment of which the terminal 24 of one of such arms will strike the actuating lever of the switch 21 which will interrupt the electrical circuit of the driving motor 25, thereby halting the rotation of the crank arm 27 and presenting the upsetting apparatus in condition to receive the next on-coming barrel. By providing the electro-magnetic brake 29, any over-run on the part of the motor 25 will be obviated so that the upsetting arms 5 are always halted in a truly horizontal position ready to receive the next barrel to be acted upon.

As most clearly indicated in Fig. 3, the switch 21, by means of which the circuit to the motor 25 is interrupted, may be positioned at a point nearer the shaft 3, so that a more delicate control over the arms 5 may be obtained, so that such arms 5 are always halted in a truly horizontal position ready to receive the next barrel. For a purpose of convenience I have designated the switch indicated in Fig. 3 by ordinals bearing prime marks similar to those employed before, designating the several parts of the limit switch shown in Fig. 1.

Other modes of applying the principle of my invention may be employed instead of the one explained, change being made as regards the mechanism herein disclosed, provided the

means stated by any of the following claims or the equivalent of such stated means be employed.

I therefore particularly point out and distinctly claim as my invention:

1. In apparatus of the character described the combination of an oscillatable shaft, barrel supporting arms secured to said shaft, spaced oppositely inclined surfaces on said arms adapted to support the barrel by engagement with its chime rings only, a crank arm secured to said shaft, means for actuating said crank arm to successively move said barrel supporting arms from a horizontal to a vertical position and return, and switch means actuated by said barrel on said supporting means for controlling said actuating means.

2. In apparatus of the character described the combination of an oscillatable shaft, spaced barrel supporting means secured to said shaft, a crank arm secured to said shaft, means for actuating said crank arm through substantially a right angle, and switch means positioned intermediately of said spaced barrel supporting means adapted to be actuated by such barrel thereon for energizing said actuating means, said barrel supporting means consisting of straight parallel arms having bevelled brackets thereon.

3. In apparatus of the character described the combination of an oscillatable shaft, spaced barrel supporting means secured to said shaft, a crank arm secured to said shaft, means for actuating said crank arm through substantially a right angle, switch means positioned intermediately of said spaced barrel supporting means adapted to be actuated by such barrel thereon for energizing said actuating mechanism, and means for de-energizing said actuating mechanism upon the completion of each cycle of operation of said barrel supporting means, said barrel supporting means consisting of straight parallel arms having bevelled brackets thereon.

Signed by me this 16th day of June, 1930.
KARL F. SNOW.
